UNITED STATES PATENT OFFICE.

OLIVER E. STEWART, OF BROOKLYN, NEW YORK.

VALVE-REMOVER.

1,113,258.

Specification of Letters Patent.

Patented Oct. 13, 1914.

Application filed December 12, 1911. Serial No. 665,485.

To all whom it may concern:

Be it known that I, OLIVER E. STEWART, a citizen of the United States, residing at Brooklyn, in the county of Kings and State 5 of New York, have invented new and useful Improvements in Valve-Removers, of which the following is a specification.

This invention relates to devices for removing valves from engines and especially 10 gas engines, and consists of a simple and inexpensive means for relieving the valve stem of its spring pressure so that the key connecting same may be readily removed to allow the valve stem to pass through the 15 opening of the valve seat as will be more fully described in the following specification, set forth in the claim and illustrated in the drawings, wherein,—

Figure 1 is a view illustrating the valve 20 connected with a four cylinder engine. Fig. 2 is a perspective view of the device, used to remove the valve and stem.

In the drawing, the four valve chambers are designated as A, B, C and D and the 25 operating shaft 5 is driven in the usual manner and carries the cams 6, 7, 8 and 9, operating upon the push rods 10, through their rollers 11 to elevate and lower same and open and close the valves. At the upper 30 end of each push rod is an adjusting screw 12, against which the stem 13 abuts, being pressed down by a spring 14, bearing upon a washer 15 which is retained by the key 16. It frequently occurs that it is necessary to remove one of the valves and in this 35 case it is difficult to remove the pressure of the spring 14 so that the key may be removed in order to allow the stem to be passed through the opening in the bottom of 40 the valve seat.

In order to elevate the washer 15, a lifter 17 is provided and consists of sheet metal having its front side 18 open, while the rear side is provided with a slot 19 through which 45 the key 16 may be removed.

In Fig. 1 the valve in the seat A is shown with its stem pressing upon the screw 12, and the roller 11 elevated to its highest point. In the valve B, the lifter 17 is shown as being inserted beneath the washer 50 15, and as the shaft 5 rotates, the stem 13 of the valve seat C is allowed to descend so that the key 16 is in position for removal.

When the key is removed through the opening 19, the stem 13 may then be pulled 55 upward so as to pass through the various openings to allow of its removal and the spring 14 will be supported by the lifter 17 as shown in connection with the valve D which has been removed with its stem, and 60 the spring retained in its proper position and under tension.

With this simple device a gas engine may be readily taken apart and repairs made or new valves and stems inserted, and it is obvious that the exact construction is not confined to the device shown in Fig. 2 but any similar lifter which consists practically of a half cylinder with a slot in its rear side could be regarded as the equivalent of the 70 device above described.

What I claim as new and desire to secure by Letters Patent is,—

A valve lifter comprising a semi-cylindrical thimble, of uniform transverse thickness, the transverse sectional area of the space within the thimble being uniform throughout the length of the thimble, the thimble being provided with a slot leading in from one edge and located opposite the 75 open side of the thimble, said thimble having at its opposite sides unbroken straight edges which extend the full length of the thimble.

In testimony whereof I affix my signature 80 in presence of two witnesses.

OLIVER E. STEWART.
